BOTTLE HANDLING DEVICE

Arthur O. Reinking, Oaklyn, N. J.

Application May 27, 1948, Serial No. 29,522

9 Claims. (Cl. 294—87.26)

1

This invention relates to bottle handling apparatus and more particularly to a portable device for gripping and supporting a plurality of bottles, or jars, in spaced relation to each other. Bottles such as are used for carbonated beverages, or so-called soft drinks, beer, milk and similar beverages are capable of being used a number of times—that is, after the bottles have been emptied they are returned to the bottling plant where they are cleaned and sterilized and then refilled for resale. Bottles of this type are usually packed in cases for transport to and from the bottling plant. These cases have partitions dividing their interior into compartments, each of which is adaptable to receive a bottle. These cases usually hold four rows of bottles with six bottles in each row so that the bottles are arranged in rows in spaced relation to each other. The compartments formed by the partitions are of such size as to freely receive a bottle but to restrict lateral movement of the bottle to prevent adjacent bottles from contacting each other to avoid breakage during the handling of the case.

When the cases of bottles are returned to the bottling plant, the bottles are removed from the cases and are fed to or placed in a machine, known as a "soaker," where they are subjected to a cleaning and sterilizing process to prepare them for refilling. The soaker is adapted to handle large quantities of the bottles at a rapid rate and the bottles are ordinarily fed into the machine by a conveyor device to which the bottles must be fed from the cases.

It has been proposed, heretofore, that bottle handling devices be employed for picking up a plurality of bottles simultaneously so as to increase the rate of feed to the soaker and to eliminate operator injury due to the handling of broken bottles. These devices have not proven satisfactory, however, particularly due to the fact that they have not been adapted to accommodate bottles that have been stuck in the cases. These prior art devices (with the exception of that shown in my copending application, Ser. No. 753,688) are so arranged that they positively grip each of the bottles, but have not been capable of releasing one bottle without releasing at least several additional bottles, as the gripping means thereof has been arranged to grip several bottles between the same members and, as a result, when the members have been separated to release a stuck bottle, they would also release at least several adjacent bottles. Therefore, all of the bottles in a group, including a stuck bottle, must be hand fed. Consequently, these prior

devices have not been successful and have enjoyed but small use in the bottling plants.

Having in mind the defects of the prior art apparatus, it is an object of this invention to provide a bottle handling device that is an improvement over the device shown in the aforesaid copending application in that it is simpler and less expensive to manufacture, yet still effective for gripping a plurality of bottles simultaneously and of releasably gripping each bottle individually so that a stuck bottle will readily be individually released without releasing other bottles of the group.

It is another object of the invention to provide a bottle handling device for gripping a plurality of bottles in spaced relation and to resiliently and yieldably grip each of the bottles individually.

In accordance with the preferred embodiment of this invention as at present devised, the bottle handling device may comprise two spaced and parallel exterior longitudinal bars fixed to opposite ends of cross bars which bridge the longitudinal bars and another pair of spaced parallel gripping bars or rods hung from the central portions of the cross pieces to be slidable thereon toward and from the exterior bars, the inner edge of each exterior bar being faced with resilient yieldable gripping material such, for instance, as a tightly wound coil spring, or the like, that cooperatively oppose said gripping bars or rods. A carrying handle structure is secured to the cross pieces and on this handle structure is mounted a manually movable operating rod for sliding the movable gripping bars or rods toward their approximate exterior bars, respectively, to cause the necks of bottles disposed between each movable bar or rod, and the exterior bar to be clamped tightly between them with such force that when the carrier is lifted the clamped bottles will normally be lifted with the device. However, the yielding faces of the exterior bars which clamp against one side of the bottle necks is such that, when the bottle is unduly restrained against being lifted, the gripping members will slide upwardly off from the bottle without causing any of the clamped bottles to be released from the device that are not unduly restrained.

The invention accordingly consists in the features of construction, combination of elements and arrangement of parts which will be set forth hereinafter, and the scope of the application of which will be pointed out in the claims that follow.

In order that a clearer understanding of this

invention may be had attention is hereby directed to the accompanying drawings forming a part of this application and illustrating certain possible embodiments of this invention, and in which:

Figure 1 is a perspective view of the device;

Figure 2 is a transverse sectional view taken substantially on line 2—2 of Fig. 1 and showing the top portion of a bottle in position to be grasped by the device;

Figure 3 is a detail of Fig. 2 and shows the gripping members of the device in gripping engagement with the bottle neck;

Figure 4 is a top view of a portion of the device in the vicinity of one of the cross pieces, the upper part of the handle structure being shown in section; and

Figure 5 is a sectional view of a detail showing the spring means placing the gripping bars in retracted normal position.

Similar reference characters refer to similar parts throughout the several views of the drawings.

Referring to the drawings, a bottle handling device in accordance with the present invention may comprise a pair of spaced parallel exterior bars 10 and 11 secured to the opposite ends of a pair of cross bars 12 and 13. The inner edges of the bars 10 and 11 are faced with resilient yieldable material, which may take the form of tightly coiled compression springs 14 and 15. These springs may be secured to the bars 10 and 11 by means of suitable brackets 16 disposed between the areas of said springs which grip the bottles and which project inwardly for a distance from the bars 10 and 11 and have their inner ends bent to encircle the springs 14 and 15, thus spacing said springs from their supporting bars 10 and 11 for the purpose which will appear. Cotter pins 34, penetrating the end brackets and extending between the convolutions of the springs, hold the springs against longitudinal displacement in the brackets but allow easy replacement of the springs.

Each of the outer bars 10 and 11 with its facing of resilient yieldable material constitutes one gripping member of a pair. The other gripping member of each pair consists of a rod 17 or 18 supported and mounted on the cross pieces 12 and 13 for transverse sliding movement, the rod 17 and the bar 10 constituting one pair of gripping members and the rod 18 and the bar 11 constituting the other pair of gripping members. At each cross-piece 12 and 13, rod 17 is slidably supported thereon by means of a connecting arm 19, the upper end of which rotatably encircles the bar 17 and has a finger formation 20 extending over and slidably resting on the adjacent cross piece. The bar 18 is similarly slidably supported on the cross pieces 12 and 13 by means of similar connecting link arms 21, the upper ends of which encircle the bar 18 and each has a finger formation 22 which slidably rests on the adjacent cross piece.

The lower ends of the connecting link arms 19 and 21 rotatably encircle an operating rod 23 disposed between and extending longitudinally of the bars 17 and 18. Suitable means, such as a cotter pin 24, penetrating the rod 23 at each end prevent the latter from sliding out of engagement with the link arms 19 and 21. Of course, the rod 23 need not be a single rod extending from one cross-bar 12 to the other cross-bar 13, but may be two short stub shafts if desired.

A bail-like handle structure is provided that

may consist, at each end, of a strip of sheet metal having an upright portion 25 in the shape of an inverted U and diverging leg portions 26 ending in flat feet portions 27 which seat on and are secured to the longitudinal outer bars 10 and 11, and, preferably also, to the cross-pieces 12 and 13 so that the legs 26 extend upwardly therefrom. A grip-handle 28 extends between and is secured to the top of the side portions 25 of the handle structure. Mounted to slide vertically in the channels formed by the inverted U portions 25 of the side members of the handle structure, are the end portions of a rod 29 positioned to underlie the grip-handle 28 in convenient reach of the finger of the gripping hand of the user and is held against becoming displaced longitudinally from the side members by a suitable washer 30 or the like, on each end of rod 29, and cotter pins 31 which penetrate the rod 29 outside of each washer 30. At each side of the handle structure is a link rod 32 which depends from the rod 29 and has its upper end encircling the rod 29 intermediate the washer 30 and the adjacent side of the handle structure. These link rods 32 extend through an aperture 35 in the cross-pieces 12 and 13, respectively, and have their lower ends encircling the rod 23 so that, as the operable rod 29 of the handle structure is raised and lowered therein, the links 32 and the rod 23 are raised and lowered likewise.

It will be apparent that as operable rod 29 is raised the gripping rod 17 will be moved toward the gripping member 10 and the gripping rod 18 will likewise be moved toward the gripping member 11. A spring 33, encircling the operating rod 23 and having its ends engaged with the gripping rods 17 and 18, biases the latter to urge them toward each other and toward the center of the bottle handling device into a normally opened position sufficiently spaced from the gripping members 10 and 11 to permit the bottle handling device to be lowered over an array of bottles so that the necks of the bottles, such, for instance, as shown at B in Figs. 2, 3 and 4, will be disposed between the gripping members of each pair. Then by raising the finger-operable-rod 29 the gripping rods 17 and 18 may be moved toward the respective springs 14 and 15 on their supporting members 10 and 11 so that each pair of gripping members will clamp against opposite sides of the bottle necks with sufficient force that when the bottle handling device is lifted all of the engaged bottles will be lifted thereby except only those, if any, that are unduly restrained against being lifted, as for instance, by foreign matter which wedges a bottle in its case.

Should any one or more of the bottles be unduly restrained against being lifted, the yielding resiliency of the facing of the longitudinal members 10 and 11 is such that, when the bottle handling device is lifted, the device will pass upwardly off of the unduly restrained bottle or bottles without causing the release of any bottle that is not unduly restrained against being lifted. Obviously, the brackets 16 which hold the resilient facing to the bars 10 and 11 are so located that when the device is in position with respect to an array of bottles to be lowered thereover the brackets 16 will be in position between the bottles so that the bottles will be clamped against the resilient yieldable facing and not against the clamp.

When the bottle handling device is used, it is carried by means of the handle 28 to a position over an array of bottles such, for instance, as

the bottles in a bottle case, and then with the finger-operable-rod 29 in its lower position, the device is lowered over the bottles; and in this adjustment of the device, the device may be freely lowered over the bottles until the necks of the bottles become disposed between the respective pairs of gripping members 10-17 and 11-18. The operator then causes the fingers of his hands holding the hand-grip 28 to grasp the operable rod 29 and pulls it up toward the handle 28. This moves the gripping bars 17 and 18 toward the fixed bars 10 and 11 and causes the bottles to be gripped by the device for lifting.

It is to be noted that the device is of exceedingly simple and inexpensive construction and does not require special dies or special machinery for its construction.

It is also to be noted that it is a very simple matter and easy to replace parts of the device. For instance, to replace the operating rod 29 it is merely necessary to remove one or both of the cotter pins 24 at one end of the rod and to slide the rod out of the bands which encircle it. The same is true with respect to the operable bar 29. To remove a spring it is only necessary to remove the cotter pins at its ends and draw the spring out of the brackets 16. For the purposes of this case the parts comprising the bail handle and the cross bars 12 and 13, or their equivalent, may be considered as a carrier frame when considering the appended claims.

Although certain specific embodiments of the invention have been shown and described, it is quite obvious that many modifications thereof are possible. The invention, therefore, is not to be restricted except insofar as is necessitated by the prior art and by the spirit of the appended claims.

That which is claimed, as new, is:

1. A bottle handling device including, in combination, a carrier frame, a pair of bottle gripping members mounted on the carrier frame, one of said gripping members having a resiliently yieldable gripping face, one of said gripping members being mounted on the frame so as to be movable into a position thereon sufficiently spaced from the other gripping member to freely receive the necks of bottles between them, said movable gripping member being normally biased to said spaced position, and an operable device engaging the movable gripping member and operable to move the movable gripping member toward the other gripping member, whereby the necks of bottles disposed between the gripping members are clamped between the gripping members with such clamping force that, when the carrier is lifted, the clamped bottles will normally be lifted thereby, the said yielding resiliency of the gripping face of the one of the gripping members allowing the gripping members to slide upwardly off from one or more of said bottles without lifting the latter when unduly restrained against being lifted.

2. A bottle handling device including, in combination, a carrier frame, a pair of bottle gripping members mounted on the carrier frame, one of said gripping members having a length of resilient yieldable gripping material and movable toward and from said edge and along one edge constituting its gripping face, one of said gripping members being mounted on the frame so as to be movable into a position thereon sufficiently spaced from the other gripping member to freely receive the necks of bottles between them, said movable gripping member being normally biased

to said spaced position, and an operable device engaging the movable gripping member and operable to move the movable gripping member toward the other gripping member, whereby the necks of bottles disposed between the gripping members are clamped between the gripping members with such clamping force that, when the carrier is lifted, the clamped bottles will normally be lifted thereby, the said yielding resiliency of the gripping face of the one of the gripping members allowing the gripping members to slide upwardly off from one or more bottles without lifting the latter when unduly restrained against being lifted.

3. A bottle handling device including, in combination, gripping members disposed to lie on opposite sides of the neck portions of a row of bottles, means mounting one of said members for relative movement toward the other member into bottle neck gripping position and away from said other member to release said bottles, one of said members having a helical spring mounted thereon in position providing the gripping surface of said member, said spring being spaced from its said supporting member to be resiliently movable to and fro relative to said member enabling the bottle head to be withdrawn from between said gripping members against the pressure of said spring while said gripping members are in bottle neck gripping position.

4. A bottle handling device including, in combination, elongated gripping members disposed to lie on opposite sides of the neck portions of a row of bottles, means mounting one of said members for relative movement toward the other member into bottle neck gripping position and away from said other member to release said bottles, one of said members having a helical spring mounted thereon in position providing the gripping surface of said member and having brackets spaced along the length of the spring intermediate its bottle gripping portions and supporting said spring spaced from said member, thus enabling the bottle head to be withdrawn from between said gripping members against the pressure of said spring while said gripping members are in bottle neck gripping position.

5. A bottle handling device including gripping members disposed to lie on opposite sides of the neck portions of a row of bottles, means mounting one of said members for relative movement toward the other member to grip the neck portions of bottles between them and away from said other member to release said bottles, one of said members including resilient yieldable means constituting the gripping surface of said member, bracket means supporting said resilient yieldable means sufficiently spaced from its said member to yieldably permit the bottle heads to be withdrawn from between said gripping members against the pressure of said resilient yieldable means while the gripping members are in bottle neck gripping position.

6. A bottle pick-up carrier adapted to be placed over and between pre-arranged rows of bottles comprising, in combination, a pair of spaced parallel bars, cross-pieces fixedly connecting said bars, another pair of spaced parallel movable bars substantially co-extensive with and between said other bars and positioned beneath said cross-pieces, link arms having one end rotatably encircling said movable bars, respectively, at the cross-pieces and their other ends extending downwardly and each having fingers extending over the cross-pieces and slidably resting thereon

whereby the cross-pieces slidably support said movable bars for movement thereon toward and from said fixed bars, a handle structure attached to said cross-pieces, manually operable means disposed between said movable bars and connecting the lower ends of said link arms and operable to move said link arms to slide said movable bars in unison toward and from their adjacent fixed bar, respectively, and resilient yieldable means mounted along the length of said fixed bars in cooperative opposition to their adjacent movable bar and freely yieldable to the pressure of bottles thereagainst, whereby upon being inserted over and between the necks of two rows of bottles, the necks of said bottles are yieldably gripped between said movable bars and resilient yieldable means and may be lifted and whereby any bottle unduly restrained against lifting will be withdrawn from between said bars and resilient yieldable means.

7. A bottle pick-up carrier as set forth in claim 6 wherein said handle structure comprises a bail-handle and a vertically movable horizontally disposed hand-bar mounted under said bail-handle to be grasped by the same handle grasping said bail and wherein said manually operable means includes a connecting rod connecting said handle-bar and the said other ends of said link arms.

8. A bottle pick-up carrier adapted to be placed over and between pre-arranged rows of bottles comprising, in combination, a pair of spaced parallel gripping bars, cross pieces fixedly connecting said bars, another pair of spaced substantially parallel movable gripping bars substantially co-extensive with and between said first bars and positioned beneath said cross-pieces, link arms having their upper ends rotatably encircling said movable bars, respectively, and having fingers extending over the cross pieces and slidably resting thereon, a lifting bail connected to said carrier, a movable operating bar disposed below and between said movable bars, the lower ends of said link arms rotatably encircling said rod, biasing means normally urging said movable bars toward each other to non-gripping position, and operable means connected with said rod to slide said movable bars against said bias and toward said fixed bars respectively, whereby two

rows of bottles may be simultaneously and yieldably gripped, when the carrier is inserted down over the necks of the bottles, and whereby one or more of said bottles unduly restrained against lifting will be automatically withdrawn from the carrier device, when the carrier device is lifted and said gripping bars are in gripping position and retaining the other of said bottles.

9. In a bottle carrier of the character described, in combination, a carrier frame having a handle and adapted to be placed by movement of the carrier on opposite sides of the neck portions of a pre-arranged row of bottles, a pair of elongated substantially parallel clamping members mounted on the frame and relatively movable into and out of bottle clamping relation, and means for relatively moving said clamping members into and out of bottle clamping relation, one of said clamping members including a support bar and resilient yieldable material mounted along the edge of said bar and sufficiently spaced therefrom for free movement and facing the other clamping member in a position to yieldably press against a side of the necks of said bottles, when clamped by and between said clamping members, whereby a row of bottles may be simultaneously and yieldably clamped by said members and lifted and whereby one or more of said clamped bottles, which are unduly restrained against being lifted, will withdraw automatically from between said members while said members remain in clamping position and retaining other of said bottles.
